J. A. & D. S. GARDNER.
CASTING APPLIANCE.
APPLICATION FILED OCT. 22, 1915.

1,195,802.

Patented Aug. 22, 1916.

UNITED STATES PATENT OFFICE.

JOSEPH A. GARDNER AND DAVID S. GARDNER, OF MEMPHIS, TENNESSEE.

CASTING APPLIANCE.

1,195,802.

Specification of Letters Patent. Patented Aug. 22, 1916.

Application filed October 22, 1915. Serial No. 57,342.

To all whom it may concern:

Be it known that we, JOSEPH A. GARDNER and DAVID S. GARDNER, citizens of the United States, both residing at Memphis, in the county of Shelby and State of Tennessee, have invented certain new and useful Improvements in Casting Appliances; and we do hereby declare the following to be a full, clear, and exact description of the invention, such as will enable others skilled in the art to which it appertains to make and use the same.

The present invention relates to improvements in casting appliances, and consists more particularly in an improved flask, together with a former for molding the impression form in the investment material poured therein; said flask being constructed in one piece and the combined mold and ladle contained therein being without joints of any kind, the molding being accomplished in a single operation.

The improved flask containing the combined mold and ladle, as constructed in accordance with the present invention, is designed for use more particularly in the centrifugal casting machine, for which we have filed an application for U. S. Patent on Oct. 22, 1915, Serial No. 57,343; it being understood, however, that the improved appliance may be employed in other forms of casting machines.

The primary object of the present invention is to provide a mold and ladle for forming dental, jewelers', or other castings, which will be constructed integral, dispensing with a joint therebetween as is now commonly had, and through which the precious metal has been found to escape; and the fire-proof investment material is arranged to be molded about the wax, or other impression form, in a single operation by coöperation of a former constructed with an integral core and peak for imposing the necessary formation therein to produce a substantially conical depression in the mold leading to the sprue, and through which the molten metal will be forced from the ladle when placed in the centrifugal machine.

With these and other objects in view the invention consists in the novel details of construction and combinations of parts more fully hereinafter disclosed and particularly pointed out in the claims.

In the accompanying drawings forming a

part of this application, and in which similar reference symbols indicate corresponding parts in the several views: Figure 1 is a side elevational view of the improved appliance including the former and flask as 60 constructed in accordance with the present invention, and assembled in readiness to receive the fire-proof investment material. Fig. 2 is a vertical sectional view of the same. Fig. 3 is a perspective view of the 65 improved former. Fig. 4 is a perspective view of the improved flask, before the investment material has been received therein. Fig. 5 is a perspective view of the improved flask containing the combined mold and 70 ladle showing the appliance ready to be mounted in a casting machine; and Fig. 6 is a longitudinal sectional view taken on the line 6—6 in Fig. 5, and looking in the direction of the arrows. 75

Referring more particularly to the drawings, the improved former is advantageously constructed of aluminum, or other suitable material, arranged to provide a flask and pattern support or solid body 1 of substantially semi-cylindrical exterior configuration, as more particularly seen in Fig. 3, and having inclined faces 2 and 3 for receiving and supporting the longitudinal edges of the flask, as hereinafter more particularly explained. 85

The support is provided substantially centrally with a ladle pattern or core 4 extending longitudinally of the same, and merging at its lower end into a base 5, 90 preferably of the circular form shown, and upon which the appliance as a whole rests. The upper end of the core 4 is extended beyond the end wall 6 of the support to provide an integral peak 7 forming a continuation of said core and projecting substantially centrally into the flask ring, as shown in Figs. 1 and 2 to produce an approximately conical depression in the mold in a manner presently more fully described. 95

In the peak 7 is a perforation for receiving the sprue wire or pin 8 upon which the wax or other impression form 9 has been impaled, and which supports the latter within the flask ring in substantially the position shown in Figs. 1 and 2. The end wall 6 of the support 1 is provided with an arcuate groove 10 for receiving the free edge of the flask ring, and centering the improved flask on the pattern support with the longi- 105 110

tudinal edges of the flask engaging the faces 2 and 3 of the support 1, and the outer transverse end resting upon the base 5.

As more particularly disclosed in Fig. 4, 5 in accordance with our invention, the flask ring 11 is approximately of cylindrical form, and is constructed of metal, or other suitable material, formed in one piece with the ladle receiver 12, which is advantageously 10 of substantially the semi-cylindrical configuration illustrated, and projects from one end of the flask ring 11, forming an unbroken continuation with the respective wall thereof, dispensing with the necessity of any 15 joint therebetween through which the precious metal could find its way.

The combined appliance is shown in the completed condition ready for mounting in the centrifugal machine in Fig. 5, where the 20 investment material 13 is molded in place with a cavity 14 constituting the ladle and occupying the ladle receiver 12 for receiving the precious or other metal, and a communicating, substantially conical, depression 15 25 in the mold in the flask ring 11 converging centrally toward the sprue hole leading to the mold cavity. A flange 16 is turned up from the outer transverse edge of the ladle flask 12 and forms an abutment against 30 which the investment material 13 is molded, and presents a smooth surface to the hand of the operator when manipulating the appliance.

In the operation of the improved appliance as above described, the former, such as shown in Fig. 3, is placed in the upright position shown in Figs. 1 and 2, with the base 5 resting upon the table or other support. The flask, in the condition shown in Fig. 4, 40 is thereupon inverted and placed over the former in that manner shown in the drawing with the flange 16 resting upon the base 5, the longitudinal edges of the ladle flask 12 engaging the faces 2 and 3 of the support 1, 45 and the free, substantially semi-circular, edge of the flask ring 11 occupying the arcuate groove 10 in the support 1, whereby the flask is centered and maintained in proper position throughout the molding operation. 50 The sprue pin or wire 8, carrying the impression form 9, may be subsequently inserted in the perforation in the peak 7 of the core 4, or said form may be inserted in such position prior to the assembly of the flask 55 upon the support, as found necessary or desirable. The fire-proof investment material is thereupon poured in the upper end of the flask ring 11, as shown in Figs. 1 and 2, and permitted to crystallize, the core 4 im- 60 posing the cavity 14 in the ladle molded within the receiver 12 of the flask as disclosed in Figs. 5 and 6, and the peak 7 the depression 15 in the investment material in the flask ring 11, also advantageously illus- 65 trated in these figures.

After the material 13 has sufficiently hardened the flask is removed from the support, simultaneously withdrawing from the perforation in the peak 7 the wax impression form 9 and pin 8, which latter will project 70 at the apex of the conical depression 15; and the result will be substantially the device in Fig. 5. This device is ready for placement in the centrifugal machine, whereupon precious or other metal will be placed in the 75 cavity 14 in the ladle and the same reduced to a molten condition, by application of a flame, and the wax form destroyed, followed by the removal of the sprue pin 8. The operation of the centrifugal machine will constrain the molten metal to flow from the cavity 14 into the depression 15 in the mold, and thence through the central sprue hole to the mold cavity in a manner which will now be well understood. 80

The improved flask containing the combined mold and ladle, as above described, is adapted for ready insertion and removal in the centrifugal casting machine described and illustrated in our application aforesaid; 90 and the same may be advantageously used in other forms of casting machines without departing from the spirit of the invention, which resides primarily in constructing the mold and ladle in a single piece with no 95 joints in order to prevent the escape and waste of metal. 85

It is obvious that those skilled in the art may vary the details of construction and arrangements of parts without departing from 100 the spirit of our invention, and therefore we do not wish to be limited to such features except as may be required by the claims.

We claim:

1. A casting appliance including a one- 105 piece flask comprising a combined ring and substantially semi-cylindrical ladle receiver without joint therebetween, investment material cast in said flask to provide a mold in the ring having a cavity and a sprue leading to the cavity, and a ladle in the receiver formed with an elongated trough having a bottom extending appreciably below said sprue and inclining from opposite ends 110 downwardly toward the center to collect the 115 molten metal in quantities therein, said trough in the ladle being in communication with the sprue leading to the mold cavity in said ring, substantially as described.

2. A casting appliance including a flask 120 comprising a ring and a ladle-receiver, investment material contained within said ring and ladle-receiver constituting a one-piece mold and ladle without joint therebetween, said mold having a sprue leading to the mold cavity and a depression in the face thereof adjacent said ladle, said ladle having an elongated trough extending substantially throughout its length beneath the level 125 of the lower part of said depression for re- 130

ceiving the metal and retaining the same in a molten state therein until brought under the influence of centrifugal action in a casting machine, substantially as described.

- 5 3. A casting appliance including a one-piece flask, comprising a ring, and a ladle-receiver extending from one end of said ring and forming an unbroken, continuous unit therewith; investment material in said 10 flask providing a mold in the ring and a ladle in the receiver merging together to form a jointless, integral whole; said ladle being substantially semi-cylindrical and providing an elongated trough for receiving 15 the metal and holding it therein in a molten condition; said mold having a cavity disposed at an appreciable height above the trough in said ladle, a substantially horizontally-extending sprue communicating with 20 said cavity, and a substantially conical depression having its apex in the sprue and merging at its lower part downwardly to meet the adjacent end of the ladle trough, substantially as described.
- 25 4. A casting appliance including a flask composed of a ring and a ladle receiver adapted to contain investment material for constituting a mold and ladle, and a flange on the outer end of said ladle receiver projecting inwardly to form an abutment 30 against which the investment material is molded, substantially as described.
5. An improved casting appliance including a flask comprising a cylindrical ring, a 35 ladle receiver constructed in one piece with said ring and extending from one end thereof, said ladle receiver being substantially semi-cylindrical, and a flange turned up from the outer end of said ladle receiver, 40 substantially as described.

6. A casting appliance including a flask composed of a ring and a ladle receiver adapted to contain investment material for constituting a mold and a ladle, means for

supporting said ring and said ladle during 45 the molding operation, a pattern on said supporting means extending into the ladle receiver for molding a ladle therein from the investment material, and an extension on said pattern projecting into said ring for 50 producing a depression in the investment material therein leading to the mold cavity, substantially as described.

7. A casting appliance including a flask comprising a ring and a ladle receiver constructed in a single piece, and a support for 55 said flask including means for holding said flask, a pattern on said support extending into the ladle receiver, and an integral peak on said pattern extending into the ring for 60 molding a combined ladle and mold in a single operation, substantially as described.

8. An improved casting appliance including a flask constructed of a ring and ladle receiver in a single piece, and a support for 65 receiving one edge of the ring and including a flange for receiving one edge of the ladle receiver, a pattern on said support extending into the ladle receiver, and a peak on 70 said pattern and extending into the ring for molding a combined ring and ladle in a single operation, substantially as described.

9. A casting appliance including a flask comprising a ring and ladle receiver constructed in a single piece, and a support for 75 said flask including a body having a slot for receiving the adjacent edge of said ring, a flange for receiving the edge of said ladle receiver, and an integral core and peak on 80 said support extending into the ladle receiver and ring for molding a ladle and mold in a single operation, substantially as described.

In testimony whereof, we affix our signatures.

JOSEPH A. GARDNER.
DAVID S. GARDNER.
